ENWRAPMENT WITH REINFORCEMENT

Clarence W. Vogt, Norwalk, Conn.

Application August 28, 1951, Serial No. 243,955

2 Claims. (Cl. 229—87)

The present invention relates to enwraps for commodities, particularly plastic substances, and embodies, more specifically, an improved form of enwrapment for products such as butter, margarine, lard, candy, cigarettes, soap, and the like. In this connection, the present invention is related to an improvement shown and described in applicant's copending application Serial No. 233,209, filed July 25, 1951, for "Enwraps for Plastic and Like Substances," and it is an object of the present invention to provide an improved enwrapment for products of the above character by means of which such products may be effectively enclosed or wrapped with a minimum amount of wrapping material and, in such condition, not only effectively packaged in such fashion as to retard loss by evaporation, etc., from the product, but also to support the product with a reasonable amount of protection against external stresses that might cause the wrapped product to be deformed.

Another object of the invention is to provide wrapping material in the form of blanks shaped and formed in an improved fashion to facilitate the wrapping operations in which the blanks are used.

Yet another object of the invention is to provide a blank, as above referred to, by means of which the positioning of the blanks in the preliminary wrapping operations may be facilitated.

Other and further objects of the invention will be apparent as it is described in further detail in connection with the accompanying drawings, wherein

Fig. 1 is a plan view of material out of which reinforcements are made in accordance with this invention, showing the manner in which cuts are made to facilitate later operations.

Fig. 2 is a view similar to Fig. 1 showing a modified form of the invention.

Fig. 3 is a view similar to Fig. 1 showing yet another form of the invention.

Fig. 4 is a plan view showing the manner in which the reinforcements are positioned upon the material of which the final blanks are formed.

Fig. 5 is a partial view in section taken on line 5—5 of Fig. 4 and looking in the direction of the arrows showing the manner in which the reinforcements are secured to the blanks as well as the nature of the final blank.

Fig. 6 is a perspective view of a completed blank formed with a reinforcement of the form shown in Fig. 1.

Fig. 7 is a perspective view illustrating the manner in which the blank of Fig. 6 is wrapped around the product to be enwrapped therein in the preliminary wrapping operation.

Fig. 8 is a partial perspective view illustrating the wrapping operation following that shown in Fig. 7.

Fig. 9 is a view similar to Fig. 8 showing the next succeeding wrapping operation.

Fig. 10 is a view similar to Fig. 9 showing the next succeeding wrapping operation.

Fig. 11 is a view similar to Fig. 9 showing the final wrapping operation.

2

Referring to Figures 1, 4, 5 and 6 there is shown one form of the invention wherein an enwrapment 12 is formed with ends 13 and 14 and sides 15 and 16 respectively. As illustrated in Fig. 7, the ends 13 and 14 are adapted to be folded in overlapping relationship in the initial wrapping operation.

Suitably adhered to the enwrapment 12 is a reinforcement 17 of a length substantially equal to the width of the enwrapment and having two end portions 18 and 19 established by the respective fold lines 20 and 21 and between which a central portion 22 is formed. Slits 23 and 24 are formed inwardly from the respective sides 15 and 16 and preferably spaced slightly from the adjacent sides of the respective ends 18 and 19, the spacing being indicated at 25. In this fashion the portion of the enwrapment forming these spaces serves to conceal the reinforcement when the enwrapment is in its wrapped condition as illustrated in Figures 10 and 11.

By providing the slits 23 and 24 as above described the movement of the enwrapment into the wrapping machine may be accurately controlled. For example, fingers may be received in the slits and the wrappers advanced by pushing against the adjacent edge of the reinforcement. Sufficient body and strength is thus provided to insure a movement and operation that can be accomplished with great precision. Moreover the slits 23 and 24 are formed to facilitate the folding operations involved in wrapping the enwrapment about desired objects or substances.

The reinforcement 17 may be formed by a cutting or stamping operation performed upon a continuous blank, if desired. Referring to Fig. 1, for example, the material of such a blank is indicated at 26 and is formed with a plurality of central slits 27 and end slits 28 and 29. A slight amount of the body of the stock is permitted to remain as connections as indicated at 30 and 31 in order that the slotted blank may be advanced effectively to be separated into the reinforcement blanks by pulling the end blank to tear the connections 30 and 31 at the point where the end blank is to be removed and adhered to the enwrapment 12. In this blank advancing operation the slits 27, 28 and 29 are conveniently utilized as a means of applying moving fingers or elements to the edges of the blanks in order that they may be pushed or moved into desired positions and in a desired fashion.

It is found particularly convenient to utilize a continuous web of wrapping material as indicated generally at 32 in Fig. 4. Such a web may be cut into enwraps along the lines 33 to form the end edges 13 and 14 of the enwrapment blanks and as illustrated in greatly enlarged form in Fig. 5, where the enwrapment is to enclose food products, a suitable layer 34 of, for example, parchment is adhered by an adhesive 35 to the material of the blank 17, this blank in turn being adhered by an adhesive 36 to a layer 37 also of parchment that is adhered to the body of the enwrapment 32 by means of an adhesive layer 38. A coating 39 (or layer of foil, if desired) may be adhered to the outer surface of the blank 32 for decorative or other purposes and the specific structure of the enwrapment and its reinforcement may be varied widely to suit different requirements.

Referring to Figures 7 to 11 inclusive an effective wrapping operation is illustrated. As above stated, the initial operation (Fig. 7) comprises bringing over the ends about an object 40 to be wrapped and in overlapping relationship. The next step is illustrated in Figure 8 in which the side end flaps 41 are folded over against the ends of the object causing the top end flaps 42 to be doubled over at an angle as shown at 43 and the bottom end of flaps 44 to be swung upwardly partially.

Following this operation the opposite side flaps 45 are folded over as shown in Fig. 9, following which the bottom flaps 44 are folded upwardly against the previous

folds, as shown in Fig. 10. The final fold is made by folding down the top flap 42 as illustrated in Fig. 11. As above mentioned, the portion 25 of the material of the enwrapping serves to conceal the adjacent edge of the reinforcement 17 and thus prevents degrading the appearance of the wrapper in its finally folded condition.

In Fig. 2 there is illustrated a modified form of the invention wherein the reinforcement is made from a blank 46 (itself similar to the blank 26) by a slightly different cutting operation. In this form central slits 47 are formed across the lines of fold 20 and 21 and side slits 48 and 49 are formed in such position that they are offset in the direction of the length of the blank 46. Connections 50 and 51 are thus formed generally in planes at angles other than right angles to the lines of fold 20 and 21 (contrary to planes at right angles thereto as shown in Fig. 1). There is thus formed tabs 52 and 53 in the ends of the reinforcements, these tabs projecting slightly beyond the sides of the wrapped object at the ends thereof to afford a convenient means by which the initial unwrapping step may be performed.

In the form of the invention shown in Fig. 3 a blank 54 (similar to blank 26) is formed by stamping or cutting out its sides to form the ends 55 of the blanks 17 with tapering sides 56 and 57. Central cuts or slits 58 are formed similar to cuts 27 the cuts forming the tapering sides 56 and 57 and the central cuts 58 being so formed as to leave connections 59 which are similar to the connections 30 and 31. In this form of the invention the material of the wrapper is slit at 60 and 61 adjacent each of the tapering sides 56 and 57 as illustrated at the right in Fig. 3. By means of the tapering side edges 56 and 57 the reinforcements may be utilized to facilitate the locating and advancing of the enwraps by means that move in endwise of the reinforcements (or otherwise with respect thereto) to receive the ends in mating elements that engage both of the tapering edges 56 and 57 at each end of the reinforcement. The wrapped package or object, in this form of the invention will have, at its ends, the bottom flaps 44 thereof of triangular shape conforming to the tapering sides 56 and 57 of the ends of the reinforcement.

It will be seen, in accordance with the foregoing, that this invention provides enwraps which not only materially strengthen the wrapped package, but greatly facilitate the operation incident to the forming of the enwrapping as well as those by which the enwrapping is applied to and wrapped around the contents thereof. In as much as the strength of the resulting package is greatly increased, the material of the enwrapping may be re-

duced in weight or strength or both, thus substantially reducing the cost of the enwrapping and the resulting wrapped commodity.

While the invention has been described with reference to the specific forms shown in the accompanying drawings, it is not to be limited save as defined in the appended claims.

I claim:

1. As an article of manufacture, flexible sheet material having sides and ends, a strip of reinforcing material thicker and stiffer than said sheet material secured to the latter and extending from side to side of said material at about its mid-portion, said strip having a mid-portion corresponding substantially in shape and dimensions to a side face of the article to be wrapped in said sheet material and end portions to overlap the ends of said article and cuts in said sheet material extending inwardly from the sides thereof adjacent at least one edge of each of the end portions of said strip and offset outwardly to one side of and immediately adjacent to the end portions of the strip.

2. As an article of manufacture, flexible sheet material having sides and ends, a strip of reinforcing material thicker and stiffer than said sheet material secured to the latter and extending from side to side of said sheet material at about its mid-portion, said strip having a mid-portion corresponding substantially in shape and dimensions to a side face of the article to be wrapped in said sheet material and end portions to overlap the ends of said article, fold lines in said strip between its mid-portion and its end portions, and cuts in said sheet material extending inwardly from the sides thereof adjacent at least one edge of each of the end portions of said strip and offset outwardly to one side of and immediately adjacent to the end portions of the strip.
